UNITED STATES PATENT OFFICE.

GUSTAVE R. THOMPSON, OF NEW YORK, N. Y., ASSIGNOR TO SHELTON-JANCKE CORPORATION, OF NEW YORK, N. Y., A CORPORATION OF NEW JERSEY.

APPARATUS AND ARTICLES FOR WAVING HAIR.

Application filed February 20, 1924. Serial No. 693,974.

This invention relates to devices or apparatus and articles for waving hair, and aims to provide improvements therein.

The invention provides a device or apparatus which produces a quicker and better wave than heretofore produced. It provides a device less liable to be injurious to the hairdresser using the device and the person whose hair is being waved, than those heretofore used. The device has more mild action on the hair, the hair having a better after condition than when waved by devices previously in use. The waving can be carried out by the present invention with considerably less current and with considerably less discomfort from heat than with prior devices or apparatus.

The invention further provides a device or apparatus and article which are simple and relatively inexpensive to make.

The invention further provides an article which is inexpensive and in convenient form for use, and which is of a nature which may be used once and thrown away, thereby providing a sanitary and labor saving article.

The invention further provides a device or apparatus in which danger from electric shocks and danger from short circuits is practically eliminated.

Several embodiments of the invention are illustrated in the accompanying drawings, in which

Fig. 1 is a vertical sectional view of one embodiment of the device and article.

Fig. 2 is a cross-sectional view on the line II-II Fig. 1.

Figs. 3, 4 and 5 are views partly in elevation and partly in section of the parts in Figs. 1 and 2 in detached positions.

Fig. 6 is a view in elevation of a second embodiment of the invention.

Fig. 7 is a cross-sectional view thereof on the line III-III Fig. 6.

Fig. 8 is a view in elevation of another embodiment of the invention.

Fig. 9 is a view in elevation (and partly in section) of another embodiment of the invention.

Fig. 10 is a view in elevation of another embodiment of the invention.

Figs. 11 and 12 are respectively a view in elevation and in vertical section of another embodiment of the invention.

Fig. 13 is a view principally in vertical sec-

tion, showing the manner of use of the invention, and

Fig. 14 is a diagrammatic view of the apparatus comprising a plurality of waving devices.

Referring to said drawings, numeral 10 designates an electrical heater, and 15 designates an envelope of any suitable kind in which the heater 10 is contained. 20 designates means for containing or holding moisture, adapted to be vaporized within the envelope by said heater 10.

The heater 10 may be of any suitable form. It is preferably a wire (flat, round, etc.) as shown in Figs. 1-3, and 6-10 inclusive. The heater may be in sheet form, as the wire gauze sheet shown in Figs. 11 and 12. It is conveniently in a form to surround, or in a form easily manipulated to surround a strand of hair wound on a curler or rod 25, shown in Fig. 13. For example, the heater may be in the form of a helical coil 27, Figs. 1 and 3, and 6 and 7, or a zigzag coil 26, Figs. 8, 9 and 10, or a flexible sheet 27, Figs. 11 and 12.

The heater 10 is preferably associated with the envelope 15 or moisture container 20, or with both, but it can be made a separate part for repeated use with or without the renewal of other parts.

As shown in Figs. 6, 7, 8 and 9, the heater is associated with and forms a composite article with the moisture container. As shown in Figs. 1 and 2, 10, 11 and 12, the heater 10, while immediately associated with the moisture carrier, is also associated with the envelope 15, which parts may constitute a composite article. The envelope 15 and heater 10 shown in Figs. 10 and 11 may constitute by themselves a composite unit or article.

The moisture holder or container 20 may be of any suitable kind or form. As shown in Figs. 1-4, it may be in the form of a tube or tubes 30, 31 of absorbent material, such as asbestos, blotting paper, flannel or the like. As shown in Figs. 6-8, the container 20 may be in the form of an absorbent covering 33 on the wire heater 10. As shown in Figs. 9, 10, 11 and 12, the moisture holder 20 may be in the form of a bag or pad formed by layers 35, 36 of fabric sewed together, as indicated at 37, and which pad may contain the heater 10, and also chemicals 40 such as used in hair waving. The moisture carriers of absorbent

material, such as shown in Figs. 1-8 may be impregnated with the chemicals, or dipped into a solution containing the chemicals prior to use.

5 The envelope 15 may be of any suitable character. As shown in Figs. 1-5, it is conveniently in the form of a tube 45 formed by winding a sheet of waxed paper. It may be of stiff cardboard as heretofore largely used. Preferably it is collapsible to admit of pressing in the ends against the wound strand to confine the vapor at the lower end of the envelope to keep it from scalding the scalp, as well understood. The upper end of the tube 15 45 may be closed in any suitable manner; by collapsing and tying; by a plug, or by a wad of cotton, etc. As shown in Figs. 10, 11 and 12, the envelope may be in the form of a sheet 47 of suitable character (as waxed paper) adapted to be wrapped around the prepared strand of hair on the curler or rod 25.

As shown in Fig. 9, the outside ply of the pad (say the ply 36) may be made of impervious material, and when the strip is wound around the strand of hair, the outer ply 36 will constitute an envelope for the vapor produced by the heating.

30 The heating element 10 preferably has leads 50, 51 adapted to extend beyond the envelope 15. These are preferably better conducting than the heater, in order not to become as hot as the heater, being of a size not to excessively heat, or formed of copper for example, or copper coated (as shown in Figs. 1 and 3) where the heater 10 is of a metal of higher resistance. Moreover one or both of these leads 50, 51, may be insulated where necessary or desirable, as by being covered by an insulating tube 55, Fig. 10, for example, or the leads may be arranged on the article in such a way as not to require insulation to prevent touching. For example, the leads 50, 51, may be arranged on opposite sides of the tube 45, Fig. 1, and have the ends thereof bent over in such manner as to clamp the tube, as shown at 57, Fig. 1. In Fig. 11, the wire 50 is on the opposite side of the sheet 47 from the wire 51. An insulating strip 59 may be placed between the part 61 of the wire and the coil where the part 59 passes alongside of the coil in Fig. 2.

55 The ends of the wire may be connected to feed wires 65, 66, in any suitable manner, as by clips 67 which grasp the ends of the leads, as shown in Fig. 14, or by a plug 68 (which may be of cork) having insulated segments 69 adapted to be inserted in the end of a tube 45, for example, as shown in Fig. 15.

60 The feed wires 65, 66, are preferably connected to a device 70 of low potential, so that shocks will not be produced if any part of the device is touched by, or comes in contact with the person.

65 The device 70 is also preferably of a character having a discharge rate approximately

that required for normal heating of each heater 10, so that a fat spark will not be produced in case of a short circuit between parts of the heater, thereby avoiding burning of the hair or parts used with the heater. For example, the part 70 may be a cell, or a secondary of a transformer rated to have a current output approximating that required for the heater which it serves. Fig. 14 shows a number of such devices 70 and envelopes 15 containing heaters, as used in waving a head of hair.

70 The location of the electric heater in immediate proximity to the moisture holder, enables the heat to become quickly effective in vaporizing the moisture, producing vapor in a much shorter time than with apparatus heretofore in use, and requiring much less electricity to produce the necessary vapor for waving. The external heat is also less than with prior devices resulting in less discomfort to persons having their hair waved, as well as to the hair-dresser. There is also absence of a so-called "baked" condition of the hair, leaving the hair in a better 80 after-condition than heretofore. Moreover, there is not the same necessity for transmission of the heat through the walls of so-called "heaters" applied externally as heretofore and the heating up of comparatively large intervening masses before the moisture is heated. Moreover, in the preferred form of the invention any radiation to the outside is from the inside of the envelope, so that all heat developed is utilized to the best advantage. 100

75 The inventive ideas herein disclosed may receive other embodiments than those herein specifically illustrated and described, as the inventive ideas may be embodied in a variety of forms.

80 What is claimed is:—

1. A device for waving hair comprising a flexible envelope adapted to enclose a prepared strand of hair, means for holding moisture in said envelope, and an electrical heater 110 in said envelope adapted to vaporize said moisture within said envelope.

2. A device for waving hair comprising an envelope adapted to enclose a prepared strand of hair, means for holding moisture in said envelope, and an electrical heater in said envelope adapted to vaporize said moisture within said envelope, said moisture holding means comprising an absorbent substance. 115

3. A device for waving hair adapted for 120 only a single use, comprising an envelope adapted to enclose a prepared strand of hair, means for holding moisture in said envelope, and an electrical heater in said envelope adapted to vaporize said moisture within said 125 envelope, said moisture holding means comprising asbestos in absorbent form.

4. A device for waving hair adapted for only a single use, comprising an envelope 130 adapted to enclose a prepared strand of hair,

means for holding moisture in said envelope, and an electrical heater in said enclosing part adapted to vaporize said moisture within said envelope, said moisture holding means comprising an absorbent substance, said electrical heater being enclosed in said absorbent substance.

5. A device for waving hair comprising a flexible envelope adapted to enclose a prepared strand of hair, an electric heater in said enclosing part, and leads to said heater of greater conductivity than said heater, whereby to generate heat only in said heater.

10. A device for waving hair designed for only a single use, comprising a flexible impervious tube adapted to enclose a prepared strand of hair, and an electric heater in said enclosing tube.

15. A device for waving hair comprising a flexible tube adapted to enclose a prepared strand of hair, and an electric heater in said enclosing tube, said tube being of impervious paper or the like.

20. A device for waving hair comprising a flexible impervious tube adapted to enclose a prepared strand of hair, an absorbent tube adapted to contain moisture, and an electric heater between said enclosing tube and said absorbent.

25. 9. An article for use in hair waving comprising a non-metallic envelope adapted to enclose a prepared strand of hair, and an electrical heater within said envelope.

30. 10. An article adapted for only a single use in hair waving comprising a non-metallic part adapted to enclose a prepared strand of hair, and an electrical heater constituting a part of said article, said enclosing part and heater being formed into a composite tube.

35. 11. An article for use in hair waving adapted for only a single use, comprising a non-metallic envelope adapted to enclose a pre-

pared strand of hair, means for holding moisture to be vaporized in said envelope, and an electrical heater constituting a part of said article, said envelope, moisture holding part and heater being formed into a composite tube.

40. 12. A hair-waving device including means adapted for only a single use adapted to envelop a prepared strand of hair comprising an absorbent material surrounding the hair, and an electric resistant heater immediately adjacent such absorbent material.

45. 13. A hair-waving device adapted for but a single use and designed to be then discarded, comprising a flexible envelope, and an electric resistant heater within such envelope adjacent the hair, whereby its heat is generated inside the envelope and close to the hair.

50. 14. A hair-waving device adapted for but a single use and designed to be then discarded, comprising a flexible envelope, an electric resistant heater within such envelope adjacent the hair, whereby its heat is generated inside the envelope and close to the hair, and a pair of wires leading from a source of electricity to said device, and terminating in conductors adapted to make temporary connection with the terminals of said heater.

55. 15. Means for waving hair comprising a plurality of devices each adapted for only a single use, each comprising a flexible tube to enclose a prepared strand of hair and an electric heater of resistant wire closely adjacent the hair, wires for leading current to each such heater, disconnectable means for temporarily connecting said wires to said heaters, and means for supplying current energy adapted to feed a limited current to such respective heaters.

60. In witness whereof, I have hereunto signed my name.

GUSTAVE R. THOMPSON.
